His Attorney

UNITED STATES PATENT OFFICE

HOWARD A. THOMPSON, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY SIGNALING SYSTEM

Application filed March 20, 1928. Serial No. 263,119.

My invention relates to railway signaling systems, and particularly to systems of the type known as three-block indication signaling.

One feature of my invention is the provision of a signaling system of this character which avoids the necessity for line wires.

I will describe one form of signaling system embodying my invention, and will then point out the novel features thereof in claims.

The accompanying drawing is a diagrammatic view showing one form of signaling system embodying my invention.

Referring to the drawing, the reference characters 1 and 1^a designate the track rails of a railway track along which traffic normally moves in the direction indicated by the arrow. These rails are divided by insulated joints 2 into a plurality of blocks, of which only three are completely illustrated in the drawing, these blocks being designated C—D, D—E and E—F, respectively.

Each block is provided with a track circuit comprising a track relay designated by the reference character T with an exponent corresponding to the location, which relay is responsive to the polarity of the track circuit current flowing in the track rails, as well as to the presence and absence of such current. That is to say, each relay comprises a contact 18 which occupies its intermediate position when the relay is de-energized, and which swings to the right-hand position or the left-hand position according as the relay is energized in the reverse or the normal direction. Track circuit current is supplied to the rails of each block in the manner hereinafter explained.

Associated with each track relay are three slow-releasing relays designated by the reference characters X, Y and Z, respectively, with exponents corresponding to the locations. Each relay X is supplied with current when the associated track relay T is de-energized, that is, when the back contact 18—18^a of this track relay is closed. Each relay Y is energized when the associated track relay is energized in the reverse direction, that is, when contact 18—18^a is closed. Each

relay Z is energized when the associated track relay is energized in the normal direction, that is, when its contact 18—18^b is closed. The circuits for the slow-releasing relays will be obvious from the drawing without further explanation, it being understood that the reference characters B and O designate the terminals of a suitable source of current for energizing these relays.

The supply of track circuit current for each block is controlled by the relays X, Y and Z of the block next in advance, as well as by a coding device designated by the reference character A with an exponent corresponding to the location. Each coding device A is provided with a circuit which passes from terminal B of a suitable source of current, through the winding of the coding device and a back contact 5 controlled by the coding device to terminal O of the same source of current. It follows that each coding device A is constantly operating to periodically open its back contacts and close its front contacts.

Each block is provided with a signal designated by the reference character S with an exponent corresponding to the location, each of which signals, as here shown, is of the four-indication type comprising two semaphore arms 3 and 4. When these arms are both horizontal, the signal indicates "stop". When the upper arm is in the 45° position and the lower arm is horizontal (see signal S^E), the signal indicates "approach restricted". When the upper arm is in the 45° position and the lower arm is in the 90° position (see signal S^D), the signal indicates "approach". When the upper arm is in the 90° position and the lower arm is horizontal (see signal S^C), the signal indicates "clear".

The operation of the system is as follows: The block immediately to the right of point F is occupied by a car or train represented by an axle and pair of wheels W, so that track relay T^F is de-energized, with the result that relay X^F is energized and relays Y^F and Z^F are both open. All of the circuits for signal S^F are open, so that this signal indicates "stop". Track circuit current is now supplied to the rails of block E—F from a bat-

tery G^F , the circuit being from the middle point of this battery, through wire 19, lower rail 1^a , relay T^E , upper rail 1, wire 20, front point of contact 8 of relay X^F , back point of contact 10 of relay Y^F , back point of contact 13 of relay Z^F , wire 23, and back point of contact 7 of coding device A^F to the lower terminal of battery G^F . The current which is thus supplied to the track rails of block 10 $E-F$ is of reverse polarity, and is periodically interrupted due to the periodic opening of back point of contact 7 of the coding device A^F . Track relay T^E is therefore periodically energized in the reverse direction, so that 15 its back contact and its reverse contact are alternately closed. Relays X^E and Y^E are therefore alternately supplied with current, and the slow-releasing characteristics of these relays are such that their front contacts remain closed and their back contacts 20 remain open as long as track relay T^E is operating in the manner specified. The 45° circuit for arm 3 of signal S^E is now closed, this circuit being from terminal B, through 25 front contact 9 of relay X^E , front point of contact 11 of relay Y^E , wire 25, and the operating mechanism of arm 3 to terminal O. The other circuits for signal S^E are, however, 30 open, and so this signal gives the "approach restricted" indication. The track circuit for block D-E is from the middle point of battery G^E , through wire 19, rail 1^a , relay T^P , rail 1, wire 20, front point of contact 8 of relay X^E , front point of contact 10 of relay Y^E , 35 back point of contact 14 of relay Z^E , wire 21 and front point of contact 6 of coding device A^E to the upper terminal of battery G^E . It follows that periodically interrupted current of normal polarity is supplied to the rails of 40 section D-E, with the result that relays X^D and Z^D are closed but relay Y^D is open. A 45° circuit for the upper arm 3 of signal S^D is closed, which circuit is from terminal B, through contact 9 of relay X^P , back contact 12 of relay Y^P , front contact 17 of relay Z^P , wire 25, and the operating mechanism of 45 arm 3 to terminal O. The circuit for arm 4 of signal S^D is also closed, this circuit being from terminal B, through front contact 9 of relay X^P , back point of contact 11 of relay Y^P , front contact 16 of relay Z^P , wire 24, and the operating mechanism of arm 4 to terminal O. It follows that signal S^D gives the "approach" indication. The track circuit for 50 block C-D is from the middle point of battery G^D , through wire 19, rail 1^a , relay T^C , rail 1, wire 20, front point of contact 8 of relay X^D , back point of contact 10 of relay Y^D , front point of contact 13 of relay Z^D , wire 22, and then through the back point of contact 6 of coding device A^D to the upper terminal of battery G^D , and also through the front point of contact 7 of this coding device to the lower terminal of battery G^D . It follows that 55 each time that the back point of contact 6

closes, current of one polarity is supplied to the track rails, and that each time the front point of contact 7 closes, current of the opposite polarity is supplied to the track rails. In other words, the current supplied to the track rails of block C-D is alternately of normal and reverse polarity, with the result that track relay T^C is alternately energized in the normal and the reverse direction, so that all three relays X^C , Y^C and Z^C are closed. 70 The circuit for arm 4 of signal S^C is open at the back point of contact 11 of relay Y^C , so that this arm is in the horizontal position. The 45° circuit and the 90° circuit for arm 3 are both closed, however, so that this arm 75 is in the 90° position. The 45° circuit is from terminal B, through contact 9, front point of contact 11, wire 25, and the operating mechanism of arm 3 to terminal O. The 90° circuit is from terminal B, through 80 front contact 9 of relay X^C , front point of contact 11 of relay Y^C , front point of contact 15 of relay Z^C , wire 26, and the operating mechanism of arm 3 to terminal O. It follows that signal S^C gives the "clear" indication. 85 The track circuit for the block next in the rear of point C is also supplied with current of alternately normal and reverse polarity, the circuit being from the middle point of battery G^C , through wire 19, rail 1^a , the 90 track relay, rail 1, wire 20, front point of contact 8 of relay X^C , front point of contact 10 of relay Y^C , front point of contact 14 of relay Z^C , wire 22, and then through the 95 back point of contact 6 to the upper terminal of battery G^C or the front point of contact 7 to the lower terminal of battery G^C . 100 Reverting to the apparatus at point F, it will be noted that relay X^F is closed, and that periodically interrupted current of reverse polarity is supplied to the rails of section 105 $E-F$. If relay X^F or its energizing circuit should fail, periodically interrupted current of reverse polarity will still be supplied to the rails of block $E-F$, the circuit being from middle point of battery G^F , through rail 1^a , relay T^F , rail 1, wire 20, back point of contact 8 of relay X^F , wire 23, and back point of contact 7 of the coding device A^F to the lower terminal of battery G^F . 110

One advantage of a system embodying my invention, is, as pointed out, that it avoids the necessity for line wires. Another advantage is, that it is immune to false clear signals due to foreign currents. 115

Although I have herein shown and described only one form of system embodying my invention, it is understood that various changes and modifications may be made therein within the scope of the appended claims without departing from the spirit and scope of my invention. 120

Having thus described my invention, what I claim is:

1. In combination, a stretch of railway 125

- track divided into blocks, a track relay for each block responsive to reversals of the polarity of current in the rails of the block, means operating when the track relay for a given block is de-energized to supply periodically interrupted current of reverse polarity to the rails of the block next in the rear whereby the track relay for the latter block is periodically energized in reverse direction 5 if the block is unoccupied, means operating when the track relay for a given block is periodically energized in the reverse direction for supplying periodically interrupted current of normal polarity to the rails of the 10 block next in the rear whereby if the latter block is unoccupied its track relay is periodically energized in the normal direction, means operating when the track relay for a given block is periodically energized in normal direction 15 and also when it is alternately energized in normal and reverse directions to supply current of alternately normal and reverse polarity to the rails of the block next in the rear whereby if the latter block is unoccupied its track relay is alternately energized in normal and reverse directions, and signals for the blocks controlled by said track relays. 20
2. In combination, a stretch of railway track divided into blocks, a track relay for each block responsive to reversals of the polarity of current in the rails of the block, three slow-releasing relays for each block, a circuit for the first slow-releasing relay closed when the associated track relay is de-energized, a circuit for the second slow-releasing relay closed when the associated track relay is energized in the reverse direction, a circuit for the third slow-releasing relay closed when the associated track relay is energized in the 25 normal direction, means operating when all three slow-releasing relays for a given block are open and also when the first relay is closed and the second and third are open to supply periodically interrupted current of reverse polarity to the rails of the block next in the rear whereby if the latter block is unoccupied its track relay is periodically energized in the reverse direction and its first and second slow-releasing relays are closed but its third is 30 open, means operating when the first and second slow-releasing relays for a given block are closed and the third is open to supply periodically interrupted current of normal polarity to the rails of the block next in the rear 35 whereby if the latter block is unoccupied its track relay is periodically energized in normal direction and its first and third slow-releasing relays are closed and its second is open, means operating when the first and third slow-releasing relays as well as when all three slow-releasing relays for a given block are closed to supply current of alternately normal and reverse polarity to the rails of the block next in the rear whereby if the latter block is unoccupied its track relay is alter- 40
- nately energized in normal and reverse directions and all three of its slow-releasing relays are closed, and signals for the blocks controlled by said slow-releasing relays. 45
3. In combination, a stretch of railway track divided into blocks, a track relay for each block responsive to reversals of the polarity of current in the rails of the block, means operating when the track relay for a given block is de-energized to supply periodically interrupted current of reverse polarity to the rails of the block next in the rear whereby the track relay for the latter block is periodically energized in reverse direction if the block is unoccupied, means operating 50 when the track relay for a given block is periodically energized in the reverse direction for supplying periodically interrupted current of normal polarity to the rails of the block next in the rear whereby if the latter block is unoccupied its track relay is periodically energized in the normal direction, means operating when the track relay for a given block is periodically energized in normal direction and also when it is alternately 55 energized in normal and reverse directions to supply current of alternately normal and reverse polarity to the rails of the block next in the rear whereby if the latter block is unoccupied its track relay is alternately energized in normal and reverse directions, a signal for each block; and means for causing each signal to give the "approach restricted" indication when the associated track relay is periodically energized in the reverse direction, the "approach" indication when the associated track relay is periodically energized in the normal direction, and the "clear" indication when the associated track relay is alternately energized in normal and reverse directions. 60
4. In combination, a stretch of railway track divided into blocks, a track relay for each block responsive to reversals of the polarity of current in the rails of the block, three slow-releasing relays for each block, a circuit for the first slow-releasing relay closed when the associated track relay is de-energized, a circuit for the second slow-releasing relay closed when the associated track relay is energized in the reverse direction, a circuit for the third slow-releasing relay closed when the associated track relay is energized in the normal direction, means operating when all three slow releasing relays for a given block are open and also when the first relay is closed and the second and third are open to supply periodically interrupted current of reverse polarity to the rails of the block next in the rear whereby if the latter block is unoccupied its track relay is periodically energized in the reverse direction and its first and second slow-releasing relays are closed but its third is open, means operating when the first and second slow-releasing relays as well as when all three slow-releasing relays for a given block are closed to supply current of alternately normal and reverse polarity to the rails of the block next in the rear whereby if the latter block is unoccupied its track relay is periodically energized in the reverse direction and its first and second slow-releasing relays are closed but its third is open, means operating when the first and second slow- 65

releasing relays for a given block are closed and the third is open to supply periodically interrupted current of normal polarity to the rails of the block next in the rear whereby if the latter block is unoccupied its track relay is periodically energized in normal direction and its first and third slow-releasing relays are closed and its second is open, means operating when the first and third slow-releasing relays as well as when all three slow-releasing relays for a given block are closed to supply current of alternately normal and reverse polarity to the rails of the block next in the rear whereby if the latter block is unoccupied its track relay is alternately energized in normal and reverse directions and all three of its slow-releasing relays are closed, a signal for each block; and means for causing each signal to give the "approach restricted" indication when the first and second associated slow-releasing relays are closed but the third is open, the "approach" indication when the first and third associated slow-releasing relays are closed but the second is open, and the "clear" indication when all three of the associated slow-releasing relays are closed.

5. In combination, a stretch of railway track divided into blocks, a track relay for each block responsive to reversals of polarity of the current in the rails of the block, means for at times supplying the rails of each block with periodically interrupted current of reverse polarity and at other times with periodically interrupted current of normal polarity and at still other times with current of alternately normal and reverse polarity, three slow-releasing relays for each block, a circuit for the first slow-releasing relay closed when the associated track relay is de-energized, a circuit for the second slow-releasing relay closed when the associated track relay is energized in the reverse direction, a circuit for the third slow-releasing relay closed when the associated track relay is energized in the normal direction, and signals for the blocks controlled by said slow-releasing relays.

6. In combination, a stretch of railway track divided into blocks, a track relay for each block responsive to reversals of polarity of the current in the rails of the block, means for at times supplying the rails of each block with periodically interrupted current of reverse polarity and at other times with periodically interrupted current of normal polarity and at still other times with current of alternately normal and reverse polarity, a signal for each block; and means for causing each signal to give the "approach restricted" indication when the associated track relay is periodically energized in the reverse direction, the "approach" indication when the associated track relay is periodically energized in the normal direction, and the "clear"

indication when the associated track relay is alternately energized in normal and reverse directions.

7. In combination, a stretch of railway track divided into blocks, a track relay for each block responsive to reversals of polarity of the current in the rails of the block, means for at times supplying the rails of each block with periodically interrupted current of reverse polarity and at other times with periodically interrupted current of normal polarity and at still other times with current of alternately normal and reverse polarity, three slow-releasing relays for each block, a circuit for the first slow-releasing relay closed when the associated track relay is de-energized, a circuit for the second slow-releasing relay closed when the associated track relay is energized in the reverse direction, a circuit for the third slow-releasing relay closed when the associated track relay is energized in the normal direction, a signal for each block; and means for causing each signal to give the "approach restricted" indication when the first and second associated slow-releasing relays are closed but the third is open, the "approach" indication when the first and third associated slow-releasing relays are closed but the second is open, and the "clear" indication when all three of the associated slow-releasing relays are closed.

In testimony whereof I affix my signature.

HOWARD A. THOMPSON.
